UNITED STATES PATENT OFFICE

2,492,083

AIR CLEANER AND DEFLECTOR THEREFOR

William H. Zelinski, Columbus, Ohio, assignor, by
mesne assignments, to Houdaille-Hershey Cor-
poration, Detroit, Mich., a corporation of Mich-
igan

Application August 21, 1946, Serial No. 692,058

9 Claims. (Cl. 183—15)

1

This invention relates to improvements in an air cleaner and deflector therefor, and more particularly to an air cleaner of the liquid bath type and a deflector for disposition in the liquid sump of the air cleaner, although the invention may have other purposes as will be apparent to one skilled in the art.

In the past, many and various types of liquid bath air cleaners have been designed for use with internal combustion engines, it being common to connect the air cleaner with the intake of the carburetor associated with the respective engine. These formerly known air cleaners, however, were not as versatile as may be desired, in that a different air cleaner had to be designed for substantially every different size of automotive engine. Automobile manufacturers in nearly every instance produce a line of motor cars varying in size and price. The engines used in a line of cars by any manufacturers also vary materially in size. While, in some instances, it has been possible to use an air cleaner suitable for an automobile engine of one manufacturer with a comparable engine of another manufacturer, it has not been possible to use the same air cleaner throughout a range of engine sizes, consistent with production economy, which does not permit use of an air cleaner having 350 cubic feet per minute capacity with an engine that requires only 250 cubic feet per minute. With these formerly known air cleaners, it was difficult, if not impossible, to effect a change in capacity of the cleaner without redesigning the cleaner, such redesigning operation requiring the provision of new tools, etc., for manufacturing the revised cleaner. Further, liquid bath air cleaners heretofore known did not in all instances establish a desired circulation of the cleansing liquid so that the dirty or sludge liquid would be kept from commingling to an objectionable extent with the lighter and relatively clean liquid, and in many cases in the use of an air cleaner having a center tube outlet for down-draft carburetors, sump liquids frequently climb the outlet conduit to a dangerously high level.

With the foregoing in mind, it is an important object of the instant invention to provide an air cleaner so that the same cleaner, without change in design, may be used with engines of different sizes over a relatively wide range, without sacrifice of economy.

Another object of this invention is the provision of an air cleaner in which the air capacity may be readily and economically changed at will without requiring any variation in the construction or component parts of the air cleaner.

2

Also an object of this invention is the provision of an air cleaner and a deflector for disposition in the liquid sump of the air cleaner, such deflector materially increasing the capacity of the cleaner without adding to the danger of carry-over of cleansing liquid through the outlet of the cleaner with exiting air.

A further object of the invention is the provision of a new and novel deflector for insertion in the liquid sump of a liquid bath air cleaner to vary the capacity of the air cleaner.

It is also a feature of this invention to provide an air cleaner and a deflector therefor, which deflector may be loosely mounted in the liquid sump of the air cleaner and held down against rattling or shifting of position by the filter unit commonly associated with liquid bath air cleaners.

It is also a feature of this invention to provide a deflector which may be inserted in the sump of a liquid bath air cleaner loosely without the aid of securing means, and which deflector is readily removable for servicing of the air cleaner.

Still another object of this invention is the provision of a liquid bath air cleaner and a deflector for disposition in the liquid sump of the air cleaner, the deflector being so arranged as to establish a circulation of cleansing liquid whereby the cleaner liquid freely circulates while the sludged or dirty liquid remains substantially dormant so that collected dirt will in the main be held quiet and not recirculated through the filter material.

Another object of the invention is the provision of a liquid bath air cleaner having a center tube outlet and a deflector for disposition in the liquid sump of that air cleaner so arranged as to eliminate the danger of oil or other sump liquid climbing the outlet conduit during operation of the cleaner, at least to a height endangering carry-over with outgoing air.

Also an object of the invention is the provision of a liquid bath air cleaner and a deflector for disposition in the liquid sump of that cleaner designed to insure adequate aspiration of liquid from the sump by traveling air without any special adjustment or equivalent operation when the deflector is placed in position.

While some of the more salient features, characteristics and advantages of the instant invention have been above pointed out, others will become apparent from the following disclosures, taken in conjunction with the accompanying drawing, in which

Figure 1 is a central vertical sectional view through a liquid bath air cleaner equipped with a deflector, and embodying principles of the in-

stant invention, certain parts being shown in elevation; and

Figure 2 is an enlarged diagrammatic view illustrating the arrangement of component parts of the air cleaner and the deflector, the view showing only one side of the air cleaner, since the other side is identical in construction.

As shown on the drawings:

In the illustrated embodiment of this invention there is shown a liquid bath air cleaner of 10 the so-called hat type for use in association with a downdraft carburetor, although it will be understood that the air cleaner may be associated with other apparatus requiring a supply of clean air. The air cleaner includes a casing comprising separable sections, an upper section and a lower section.

The upper casing section includes an outer wall 1 which may be lock seamed or equivalently secured to an overall cover 2. The upper portion of the wall 1 is outwardly turned to be joined with the cover, which is of greater diameter than the wall, as seen at 3 in Fig. 1, so that this part of the cleaner will function as a hood over the inlet opening to be later described. Extending centrally downwardly through the upper section is a center tube outlet conduit 4 connected to the inside of the cover 2 by a suitable flared spider arrangement 5 having relatively large openings 6 therein through which traveling air may enter the outlet conduit 4. Between the conduit 4 and the wall 1 an annular filter element is disposed. This element may include a mass of filter material 7 which may be of any suitable material, such as wavy metallic wire or ribbon, animal hair, vegetable fiber, etc., treated in any desirable manner, and the unit may be removable or fixed in position as may be desired. Depending upon what particular material may be used for the filter medium 7, hardware cloth or equivalent screen-like elements 8 and 9 may be disposed at the top and bottom of the filtered mass in order to retain it properly in position.

The lower casing section is in the general form of a cup, and this section defines a liquid sump for the air cleaner. This section includes an outer upstanding wall 10 having the upper margin inwardly rolled as at 11 to lessen restriction to entering air. This wall 10 is of larger diameter than the wall 1 on the upper casing section so that a downwardly leading path 12 for incoming air is defined between these walls. As seen clearly in Fig. 1, the wall 10 terminates well below the junction between the wall 1 and the cover 2 so as to define an annular air inlet opening 13.

Below the inlet passage 12 the lower casing section is given a curvate contour 14 merging into an upwardly sloping inside wall 15 to define an annular trough-like portion 16 in the liquid sump. The wall 15 merges into a curvate cross connection 17 which in turn merges into a substantially vertical wall 18 leading downwardly to a bottom 19 which at its inner portion curves upwardly and may be secured by spot welding or in an equivalent manner as at 20 to an outlet conduit section 21. This arrangement defines an inner central well 22 in the liquid sump, preferably somewhat deeper than the trough-like portion 16 which surrounds the well.

The outlet conduit portion 21 may be secured in any desirable manner to the intake of a carburetor or to another device requiring a supply of clean air. This conduit is provided near its upper end with a gasket holding arrangement 23

for a gasket 24 against which the conduit portion 21 of the upper casing section seats when the two casing sections are joined together. The casing sections may be maintained or joined together during operation by means of a Z bar 25 carried in the conduit portion 21 of the lower section to which is connected an elongated bolt 26 that extends through the cover 2 for external engagement by a thumb nut 27.

The structure so far described will operate satisfactorily as an air cleaner for certain capacity engines. It will be noted that the air cleaner does not require a baffle associated with the liquid sump by virtue of the particular construction of this sump as above defined. Incoming air entering the annular inlet 13 in descending through the passage 12 will carry the sump liquid contained in the trough-like portion 16 of the sump immediately up into the filter mass. The depth and size of the trough-like portion 16 limits the amount of sump liquid that may be initially carried into the filter mass upon starting of operation. This liquid is commingled with the air, and circulated through the lower portion of the filter mass, the upper portion of the filter mass removing any entrained liquid and in some cases extremely fine particles of dirt from the outgoing air, so that the air leaving the cleaner by way of the conduit sections 4 and 21 is in a clean dry state.

Now, while the air cleaner as above described provides highly satisfactory and highly efficient operation for a certain capacity, if the air cleaner is to be used with a larger engine it must be made to satisfactorily operate for a larger capacity of air. If more air is merely drawn through the cleaner, without anything else being done, the capacity of the cleaner cannot be increased materially, that is above the commonly provided safety factor, without pulling cleansing liquid over into the carburetor along with outgoing air. In order to accomplish this purpose, namely, to materially increase the capacity of the cleaner, and yet still have an adequate safety factor remaining, I have provided a deflector for insertion in the liquid sump. This deflector may be fabricated of several pieces to facilitate manufacture, but is preferably an integral structure when completed.

In the illustrated embodiment, the deflector comprises an upstanding or substantially vertical body wall 28 which is longer than the distance between the bottom of the liquid sump and the filter element. On the outside of this wall 28 a trough-like formation is provided which includes an outwardly and downwardly sloping bottom 29, an outer upright or substantially vertical wall portion 30 and the upper margin of this wall portion 30 is preferably inwardly turned as indicated at 31.

As illustrated, the deflector is annular and is seated inside the inner well portion 22 of the liquid sump. The deflector is of such a size that the outer wall portion 30 of the trough-like formation is adjacently disposed to the vertical wall portion 18 of the liquid sump. There is a gap 32 between these adjacent wall portions through which liquid might be aspirated from the sump by air traveling through the cleaner. Such a gap of 0.03 inch has been found satisfactory. It will be noted that the trough-like formation on the outside of the wall 28 is above the bottom of the wall and above the bottom of the liquid sump, and in the wall 28 below this trough-like portion 75 there is an annular series of apertures or open-

ings 33 and a satisfactory size for these openings has been proven to be such that their combined area is approximately equal to one-third of the cross-sectional area of the gap between the wall portions 18 and 30. It should be understood that where relative sizes are given herein they are given by way of example only and not by way of limitations, for the purpose of enabling one skilled in the art to reproduce the invention herein disclosed.

To facilitate manufacture, as shown in the drawings, the wall 28 is preferably fabricated from two initially separate pieces, an upper piece having the trough-like formation thereon and a lower cylindrical piece having the apertures 33 therein. These two pieces are spot welded or equivalently secured together to form an integral structure.

The deflector is merely placed loosely in the liquid sump of the cleaner. Either of the wall portions 18 or 30 may be provided with spaced pressed out detents 34 to insure the positioning of the deflector in the proper location so as to maintain the gap 32 uniform throughout its length. In the illustrated instance these detents are shown formed in the wall 18 of the cleaner casing, but obviously they could be equally as well formed in the wall portion 30 of the deflector. The deflector is held in position against rattling by the filter element. As seen clearly in the drawings, the height of the deflector is preferably such as to indent the lower portion of the filter mass and thus insure a solid seating of the filter mass on top of the deflector.

With the deflector in place, it will be noted that the space below the filter mass is substantially divided, and the inner well portion 22 of the liquid sump is also divided into two compartments. Communication is established between these compartments through the apertures 33 in the wall 28 of the deflector.

With this arrangement, incoming air passes through the outer trough-like portion 16 of the sump, up over the sloping wall 15, and then this incoming air by virtue of the greater room begins to expand substantially at the point indicated by the lead line from numeral 35 in Fig. 2. As the air expands, it will of course continue its travel through the cleaner, and the air will contact the turned in margin 31 on the outerwall portion 29 of the deflector. A contact here is desirable so that there will be adequate aspiration of sump liquid through the gap 32. The height of the wall 30 on the trough-like portion of the deflector must not be too great nor too little. If it is too great so that the traveling air may contact it at a high point, that is a point materially above the part 17 between the walls 15 and 18 of the liquid sump, there will be little or no aspiration of sump liquid through the gap. If the wall 30 is so short that traveling air may contact it or can contact it at a point down below the part 17, there is a good likelihood of some air passing down into the sump through the gap creating an adverse condition of operation. The above examples are true to a much greater extent in the event the wall 30 would be perfectly straight. However, this wall 30 has been made with an inwardly turned upper margin so that air striking it is caromed upwardly into the filter mass, and the height of this wall is substantially that of the part 17, or a trifle thereabove, so that there will be a clean contact of air from the point 35 over against the curved portion 31 of

the wall 30 and proper aspiration of cleansing liquid results.

With the deflector in place, it will also be noted that the air will strike the upper part of the wall portion 28 and then go up into the filter mass without traveling too far across the lower portion of the filter mass. This wall portion 28 thus deflects the air, and prevents the air from causing sump liquid to climb up the outlet conduit to a point that would be dangerous from the standpoint of carry-over of cleansing liquid. With the deflector in place the capacity of the cleaner is greatly increased. For example, a cleaner having a capacity of 250 cubic feet per minute without the deflector will have a safe capacity of 350 cubic feet per minute with the deflector. Thus, the same cleaner may be utilized throughout a relatively wide range of engines without any change in the structure of the component parts of the cleaner. The variation is caused merely by the addition or removal of the deflector, depending upon which way it is desired to vary the capacity of the cleaner.

During operation, as oil or other sump cleansing liquid descends from the filter mass, a goodly portion of it will fall inside the deflector wall 28. Circulation is established by means of the openings 33 so that that portion of the sump adjacent the gap 32 is insured of an adequate supply of cleansing liquid for aspiration purposes. By virtue of the action of the air, most of the heavier sludged or dirt laden liquid will eventually arrive inside the wall 28 of the deflector and in the trough-like formation on the outside of this wall. In either location the very heavy dirt laden liquid and the dirt removed from the traveling air will be in a relative zone of quietude and will lie dormant to a great extent. The lighter and unburdened cleansing liquid may pass readily through the openings 33 and be recirculated, but there is little chance of dirt having once been removed from the air from again being recirculated through the lower part of the filter mass.

In servicing the cleaner, it is a simple expedient to remove the thumb nut 27, lift off the upper casing section together with the filter mass, and then the entire deflector may be readily lifted out of the liquid sump. The deflector may be cleaned, and the lower casing section may be emptied of sump liquid and accumulated dirt, and then refilled with clean sump liquid to a point substantially equal with the lower end of the upper casing section wall 1. The deflector may then be dropped in place and the upper casing section put back into operative position with the filter element resting upon the deflector.

From the foregoing comment it is apparent that I have provided a highly efficient air cleaner and deflector arrangement which establishes a desirable circulation of cleansing liquid and which insures adequate aspiration of liquid from the sump when the cleaner is operating at a high capacity without any necessity of any special adjustments of any kind. It will further be noted that with the aid of the deflector, the same cleaner without any change in construction may be used at a considerably higher capacity than without the deflector, thus enabling the same air cleaner to be used through a relatively wide range of engine capacity. Furthermore, the entire structure is relatively simple, and economical both from the standpoint of manufacture and servicing.

It will, of course, be understood that various details of construction may be varied through a

wide range without departing from the principles of this invention and it is, therefore, not the purpose to limit the patent granted hereon otherwise than necessitated by the scope of the appended claims.

I claim as my invention:

1. In an air cleaner, a casing having a liquid sump in part defined by a substantially vertical wall over which air passes in traveling through the cleaner, a deflector in said sump and including an upright body wall higher than said sump wall and spaced therefrom, a trough-like formation on the outside of said deflector body wall including an upstanding wall disposed adjacent said sump wall but spaced therefrom to leave a gap therebetween through which sump liquid may be aspirated by traveling air, and said deflector body wall having a series of holes therein below said formation, said holes having a total area equivalent to a gap less than half the size of said gap.
2. In an air cleaner, a casing having a liquid sump in part defined by a substantially vertical wall over which air passes in traveling through the cleaner, a deflector in said sump and including an upright body wall higher than said sump wall and spaced therefrom, a trough-like formation on the outside of said deflector body wall including an upstanding wall disposed adjacent said sump wall but spaced therefrom to leave a gap therebetween through which sump liquid may be aspirated by traveling air, the upper margin of said formation wall being inwardly turned, the upper end of said sump wall being rounded outwardly, and said formation wall extending sufficiently high relatively to said sump wall for traveling air to contact said formation wall and aspirate sump liquid through said gap.
3. In an air cleaner, a casing having spaced inlet and outlet openings and a liquid sump therein, a filter element in said casing above said sump, a deflector element seated freely on the bottom of said sump and held in position by said filter element resting thereon, said deflector element including an upright body wall of sufficient height to indent the lower part of said filter element and thus divide said sump into separate concentric compartments, and a series of openings in said deflector wall to establish communication between said compartments below the level of cleansing liquid in said sump.
4. In an air cleaner, a casing having a center tube outlet for clean air and an annular inlet passage spaced from said outlet, said casing having a sump for cleansing liquid at the bottom thereof adjacent the path of air traveling from said inlet to said outlet, a filter element above said sump around said outlet tube, and a deflector freely seated in the bottom of said sump and including an upstanding wall with its lower edge seated on the bottom of said sump and its upper edge in contact with and indenting said filter element concentrically, said wall dividing the space between the sump and filter element to limit the path of air traveling through the cleaner and thus prevent liquid climbing the outlet tube and also increasing the capacity of the cleaner.

5. In an air cleaner, a casing having separated inlet and outlet openings, said casing having a liquid sump in the bottom thereof, a filter element in said casing above said sump, the bottom of said casing being curvate in the region beneath the inlet to define an annular trough-like portion

of said sump, the wall of said trough-like portion farthest from the inlet being upwardly sloping to guide air easily into said filter element, a substantially vertical wall spaced from said sloping wall and defining another well-like portion of said sump, said walls being connected by a curved junction at the tops, and a deflector in said sump including a body wall extending vertically to said filter element and dividing the well-like portion of said sump into separate concentric compartments.

6. In an air cleaner, a casing having a liquid sump in the bottom thereof partially defined by a substantially vertical wall, said casing having separated inlet and outlet openings, a filter element above said sump, a deflector freely seated on the bottom of said sump below said filter element, said deflector being held in position by said filter element resting thereon, said deflector including an upright wall portion spaced from said sump wall to define an aspiration gap therebetween, and one of said walls having spaced projections thereon to maintain said gap uniform throughout its length.
7. A deflector for free disposition in the liquid sump of a liquid bath air cleaner, comprising a substantially cylindrical and vertical body wall, and a trough-like formation including a bottom and a second upright wall spaced from said body wall, said formation extending outwardly from and around said body wall above the lower end of said body wall, said body wall extending below said formation to seat freely on the bottom of the liquid sump of the cleaner.
8. A deflector for free disposition in the liquid sump of a liquid bath air cleaner, comprising a substantially cylindrical and vertical body wall, and a trough-like formation including a bottom and a second upright wall spaced from said body wall, said formation extending outwardly from and around said body wall above the lower end of said body wall, said body wall extending below said formation to seat freely on the bottom of the liquid sump of the cleaner, said body wall having a series of apertures therein below the bottom of said trough-like formation.
9. In an air cleaner, a casing having a liquid sump in part defined by a substantially vertical wall over which air passes in traveling through the cleaner, a deflector in said sump and including an upright body wall higher than said sump wall and spaced therefrom, a trough-like formation on the outside of said deflector body wall including an upstanding wall disposed adjacent said sump wall but spaced therefrom to leave a gap therebetween through which sump liquid may be aspirated by traveling air, and said deflector body wall having a series of holes therein below said formation.
